UNITED STATES PATENT OFFICE.

WILLIAM VON DAAKE, OF VANCOUVER, WASHINGTON.

RAILWAY CATTLE-GUARD.

SPECIFICATION forming part of Letters Patent No. 739,590, dated September 22, 1903.

Application filed August 30, 1902. Serial No. 121,683. (No model.)

To all whom it may concern:

Be it known that I, WILLIAM VON DAAKE, a citizen of the United States, residing at Vancouver, in the county of Clarke and State of Washington, have invented new and useful Improvements in Railway Cattle-Guards, of which the following is a specification.

This invention relates to railway cattle-guards for preventing cattle and other stock from passing from one inclosure to another without interfering with the free passage of railway-trains, and has for its object to provide a cattle-guard of the character referred to which will be strong, durable, inexpensive to manufacture, and simple and efficient in operation.

To these ends my invention consists in the features and in the construction, combination, and arrangement of parts hereinafter described, and particularly pointed out in the claims following the description, reference being had to the accompanying drawings, forming a part of this specification, wherein—

Figure 1 is a sectional view taken transversely of the railway-rails. Fig. 2 is a detail perspective view of the central section of the cattle-guard, and Fig. 3 is a similar view of one of the side sections.

In constructing my improved guard I provide a plurality of rectangular frames, and in each of said frames I journal a plurality of parallel rollers arranged in close proximity to one another. The frames are secured to the railway-ties between the track-rails and on each side thereof in such manner that the rollers lie parallel with the rails, whereby when cattle or other stock attempt to pass over from one inclosure to another across said rollers the latter will turn under the feet of the cattle and cause the cattle to slip, whereby they are unable to secure a sufficient foothold to cross the guard.

Each of the frames referred to comprises two end pieces 1^a and two side pieces 2^b. The end pieces each consists of an angle-iron—that is to say, a strip of metal bent into substantially L shape—the vertical flanges of the said end pieces being provided with a plurality of perforations 4^a for the reception of the journals of the guard-rollers, while the horizontal flanges 5 of said end pieces are provided with screw-holes 6 for the passage

therethrough of screws for attaching the frames to the railway-ties. Each of the side pieces 2^b of the frames consists of a metallic strip having its ends bent at right angles to the body of the said side pieces, as at 17. The angular ends 7 of the two side pieces 2^b are disposed against the outer faces of the end pieces 1^a and are secured thereto by bolts. 55 Journaled between the end pieces of each of the frames is a series of rollers each consisting of a metallic tube 9, the opposite ends of which are provided with gudgeons or journals, which are journaled in the perforations 4^a of the end pieces, whereby the rollers are free to revolve about their longitudinal axes, and in practice said rollers are so arranged that their peripheries lie in relative close proximity to one another. In putting the 70 guard in place the sections are laid upon the ties between the railway-rails 13 and on each side thereof in such manner that the guard-rollers lie parallel with the said rails. After the frames have been placed in position on the ties they are firmly secured in place thereon by screws which are screwed through the perforations 6 in the horizontal flanges 5 of the frames and into the railway-ties. Preferably a fence 14 is erected 75 on each side of the cattle-guard to prevent the cattle or other stock from stepping around the terminations of the fence which separates one inclosure from another. As shown, the guard-rollers are arranged in inclined 80 planes which converge toward the railway-rails. The numeral 16 indicates the central section, which is arranged between the two rails of the track and consists of a frame constructed in the manner hereinbefore referred 85 to, the two end pieces 1^a of said frame being arch-shaped—that is to say, are highest at the center and inclined downwardly in opposite directions from the center toward the ends—and the perforations 4^a in which the 90 rollers 9 are journaled are arranged an equal distance from the upper edges of said end pieces. The central roller of the frame 16 is therefore the highest, and each succeeding roller on either side of said central roller is 95 slightly lower than said central roller and the rollers as the two rails are approached being disposed lower and lower. The frames of the side sections 17 are made in the man-

ner before described, excepting that the outer side 2^a of each of said outer sections is higher than the opposite inner side 2^b , and the end pieces 4^b are inclined or gradually increase in height from the inner side pieces 2^b to the outer side pieces 2^a , and the bearings 4^a in which the rollers 9 are journaled are formed equidistant from the upper inclined edges of said inner pieces, whereby the rollers of each side section lie in inclined planes which extend downwardly toward the track-rail, as is most clearly shown in Fig. 1 of the drawings. It will be seen that the guard-rollers are disposed in inclined planes that converge toward the track-rails, whereby when the cattle attempt to cross said guard their feet are not only caused to slip from under them owing to the rotation of the guard-rolls, but they are also caused to slip sidewise owing to the inclined position of said rollers. It will be obvious that instead of making each of the central sections in one frame, as shown in Fig. 2, said central section may consist of two side frames arranged between the two rails of the track, the highest sides of said frames abutting, as shown by the dotted lines in Fig. 1 of the drawings, thus making all of the frames interchangeable.

Having described my invention, what I claim is—

1. A railway cattle-guard comprising a plurality of frames arranged longitudinally between the railway-rails and on each side thereof, longitudinal rollers journaled in the said frames, the said rollers being disposed in inclined planes, converging toward the two railway-rails substantially as described. 30

2. A railway cattle-guard comprising a plurality of rectangular frames each of said frames comprising two end pieces having means for attaching the same to the railway-ties and two side pieces rigidly secured to said end pieces, said frames being arranged longitudinally between the railway-rails and on each side thereof, longitudinal rollers 40 journaled in the end pieces of said frames, the said rollers being disposed in inclined planes converging toward the two railway-rails, substantially as described. 45

In testimony whereof I have hereunto set my hand in presence of two subscribing witnesses.

WILLIAM VON DAAKE.
